UNITED STATES PATENT OFFICE.

JOHN WEDIN, OF MINNEAPOLIS, MINNESOTA.

WRENCH.

1,085,183.

Specification of Letters Patent. Patented Jan. 27, 1914.

Application filed July 17, 1913. Serial No. 779,463.

To all whom it may concern:

Be it known that I, JOHN WEDIN, a citizen of the United States, residing at Minneapolis, in the county of Hennepin and State 5 of Minnesota, have invented certain new and useful Improvements in Wrenches, of which the following is a specification.

This invention relates to improvements in wrenches and its object is to provide a 10 wrench in which the jaws thereof may be instantly adjusted to any desired position with relation to each other and then positively locked in such adjusted position.

Another object is to produce a wrench 15 that is simple to operate, durable, efficient in use and not easy to get out of order.

With the foregoing and other objects in view the invention consists in the combination and arrangement of parts to be herein- 20 after fully described in the following specification, pointed out in the claims and illustrated in the accompanying drawing which forms a part of said specification and in which—

25 Figure 1 is a side elevation of my improved wrench with a portion of the handle and sliding jaw shown in section. Fig. 2 is a rear elevation. Fig. 3 is a section taken on line 3—3 of Fig. 2. Fig. 4 is a section taken on line 4—4 of Fig. 3. Fig. 5 is a section taken on line 5—5 of Fig. 3.

Like reference characters indicate corresponding parts throughout the several views.

1 is the shank of my improved wrench 35 which is provided with the fixed terminal jaw 2 and the handle 3. The said handle is apertured longitudinally for the reception of a shell 4 which is projected beyond said handle and threaded upon each end; one 40 end being for reception of the nut 5 and the other end to engage the threaded apertured portion of a yoke 6 which is secured to the shank 1 abutting the handle 3. Within the shell 4 one end of a plunger 7 is disposed which at its opposite end is secured to the movable jaw 8 and said plunger passes through the knurl 9 and through the casting 10, the latter being secured to the shank 1 as at 11.

50 The knurl 9 extends into the recessed portion 9^a of the shank and is formed with an integral interior annular member 12 disposed about the plunger 7 and threaded

upon its periphery as at 13 to engage the threaded annular termination 14 of risers 15 55 partly disposed within said knurl and projected up into the said casting 10 and terminating in jaws 16 disposed about the plunger 7 and curved to conform to the interior configuration of the said casting. The 60 interior surface of the casting is formed with grooves 17 in which lugs 18 on jaws 16 are slidably disposed that bear against the jaws 16. To adjust the wrench the movable jaw is moved along the shank 1 as desired 65 and the knurl 9 is then turned in a direction that will cause the member 12 to raise the risers 15 thus clamping the jaws about the plunger and locking the same against longitudinal movement and at the same time locking 70 the movable jaw of the wrench in its adjusted position. Turning the knurl in the opposite direction will release the jaws 16 from engagement with the said plunger.

What is claimed is:—

1. In a wrench comprising a recessed shank carrying a terminal jaw and an apertured handle, a movable jaw slidable upon said shank, a shell carried by said apertured handle, a plunger partially disposed within 80 said shell and connected to said movable jaw, a knurl disposed about said plunger and partly projected into the recessed portion of said shank, a threaded annular member formed integral with and disposed within 85 said knurl and encircling said plunger, an interiorly grooved casting secured to said shank above said knurl and encircling said plunger, lugs slidable in the grooved portions of said casting and clamping means for 90 said plunger partly disposed within said knurl and projected into said casting operatively associated with the aforesaid annular threaded member.

2. In a wrench comprising a recessed 95 shank provided with a terminal jaw and an apertured handle, a movable jaw slidable upon said shank, a shell carried by said apertured handle, a plunger partially disposed within said shell and connected to 100 said movable jaw, a knurl disposed about said plunger and partly projected into the recessed portion of said shank, a threaded annular member formed integral with and disposed within said knurl and encircling 105 said plunger, an interiorly grooved casting

secured to said shank above said knurl and encircling said plunger, lugs slidable in the grooved portions of said casting and risers, partially disposed within said knurl in engagement with said threaded annular member, projected into said casting and terminating in jaws disposed about said plunger.

In testimony that I claim the foregoing as my own I have hereto affixed my signature in the presence of two subscribing witnesses. 10
JOHN WEDIN.
